UNITED STATES PATENT OFFICE

FREDERICK B. HEITKAMP, OF CINCINNATI, OHIO, ASSIGNOR TO THE CINCINNATI MILLING MACHINE COMPANY, OF CINCINNATI, OHIO, A CORPORATION OF OHIO

DESIGN FOR A MACHINE-TOOL RATE-INDICATING DIAL

Application filed October 28, 1929. Serial No. 33,186. Term of patent 14 years.

To all whom it may concern:

Be it known that I, FREDERICK B. HEITKAMP, a citizen of the United States, residing at Cincinnati, in the county of Hamilton and State of Ohio, have invented a new, original, and ornamental Design for a Machine-Tool Rate-Indicating Dial, of which the following is a specification, reference being had to the accompanying drawing, forming part thereof.

Figure 1 is a plan view of a machine tool rate indicating dial, showing my new design.

Figure 2 is a perspective view thereof.

I claim:

The ornamental design for a machine tool rate indicating dial, as shown.

In testimony whereof, I affix my signature.

FREDERICK B. HEITKAMP.
